UNITED STATES PATENT OFFICE.

HEMAN CLARK, OF NEW YORK, N. Y.

DREDGING AND GRAPPLING APPARATUS.

SPECIFICATION forming part of Letters Patent No. 326,627, dated September 22, 1885.

Application filed May 23, 1885. (No model.)

To all whom it may concern:

Be it known that I, HEMAN CLARK, of the city, county, and State of New York, have made an invention of a new Dredging and 5 Grappling Apparatus; and I hereby declare that the following is a full, clear, and exact description of the same, reference being made to the accompanying drawings, making part thereof.

10 My dredging and grapping apparatus is designed to be used for excavating or removing various kinds of material by means of power applied to it through flexible connections for lowering and raising it and the load, and also, by means of power directly applied 15 through flexible connections to the closing and opening of compound tongs or grapple, for seizing and releasing the load at any position desired by the operator within the reach 20 of the apparatus.

In connection with my apparatus I employ hoisting and lowering machinery worked by power, and located at some convenient point to be controlled by the operator. Sometimes 25 I place said hoisting machinery and the boiler and engine by which it is driven on a boat or car, and to the same attach or arrange pumps and reservoirs for forcing and retaining air under pressure. Sometimes I place a dynamo-machine for the generation of electricity. 30 In the former case I carry flexible pipes from the air-reservoirs to the dredging apparatus in order to act on a piston, to be hereinafter described, for opening and closing the compound tongs. In the latter case I connect 35 insulated wires in a complete metallic circuit to convey electricity to a small dynamo-machine connected directly to the apparatus, to furnish power for moving in any convenient 40 and practicable way, the compound tongs for seizing and releasing the load of material.

My invention consists in certain combinations of mechanism specifically set forth at 45 the end of this schedule.

In order that persons skilled in the art may understand, make, and use my apparatus, I will proceed to describe the way it has been constructed by me, referring to the 50 drawings, in which the same parts are desig-

nated by the same letters in the different figures.

Figure 1 represents a side view of the dredging apparatus, the form of the tongs making the inclosure complete. Fig. 2 represents a side view of the same, with the tongs of the grapple forming a cage, but not inclosing the entire surface of the sphere or its contents. Fig. 3 represents a vertical section through the center of the piston and cylinder of the apparatus, the plane passing at right angles to the cross-head of the piston vertically through two opposite connecting-levers and in front of one pair of tongs. Fig. 4 represents a top view of the combining-ring 65 A, showing the position of attachment of the connecting-levers B.

The apparatus is suspended from a chain or other flexible support by means of the eye C in the cross-bar K, to which latter is attached the vertical supporting and guiding rods H H. The rods H H are connected at their lower ends to the frame V, to which the cylinder D is bolted. The frame V is provided with a depending bar, V', grooved with a circular 75 channel, W, to receive a ring having radial horns with eyes, to each of which is pivoted the upper end of one of the tongs P. The cylinder D, attached to frame V, is supplied with two pipes, the pipe S connecting with 80 the top and the pipe S' with the bottom of the cylinder. These pipes extend to the air or water under pressure or other reservoir of force, and are separately or together provided with valves or cocks to enable the operator to admit a pressure of air or such like fluid alternately to the top and bottom of the cylinder, and also to exhaust or let it out alternately from the top and bottom of the cylinder, after the manner of an ordinary air 85 or steam engine, the admission and exhaust of the pressure being under the control of the operator as to time and pressure.

In the cylinder is fitted a piston, E, to which is attached a piston rod, F, extending through 95 packing and a gland to the cross-head G, and firmly connected, so that the cross-head sliding on the guides H H may raise and lower the combining-ring A, bolted to the rods l l l, and the latter to the ends x x of the cross-head. 100

To the combining ring A are bolted, at equal distances apart, the radial bars M, eight in number in the present instance, and the bars M are provided at their projecting ends with 5 eyes, to which the upper ends of the connecting-
rods B are jointed. Each of the connecting-
rods B is jointed to a radial bar, M, and also
at the lower end to the tongs P by the eye Q.
Each and all the tongs are pivoted to the ring
10 on bar V' by means of an eye, Y, in the up-
per end thereof, and the eyes in the ring are
held in the groove or channel W in V'. The
tongs P are so shaped and connected that
15 their lower ends are united at T when closed
together, and inclose substantially a spherical
form, whether in whole or in part depend-
ing upon the horizontal circumferential width
of the tongs.

When the dredge or grapple is to be oper-
20 ated, it is attached to a chain or rope wound
around a hoisting-drum, and allowed to hang
by its gravity. To the reservoir of compressed
air the pipes S and S' are connected, (if such
25 is the force to be used,) and the cock or valve
of the pipe S is turned to allow the air-pressure
to pass from the reservoir through the pipe S
to the lower end of the cylinder D and under
the piston E. The exhaust cock or valve in
30 S' having been opened to the air, the pressure
on the piston will cause it to rise and carry
with it the cross-head G, the combining-ring
A, and the connecting-rods B. As the latter are
35 attached by pivots to the tongs P, they open at
T, turning around the pivots X X until the
piston reaches the upper head of the cylinder.
In the meantime the compressed air has been
40 filling the cylinder and the piston has forced
the air above it through the pipe S' to the at-
mosphere. The tongs may be opened before
the apparatus has been lowered to its work or

after it has been so lowered. If the former, the
whole apparatus, with its flexible tubes, is
now lowered, with the tongs open, to the bot-
tom of a river-bed or other place to be used,
and the apparatus is allowed to rest by gravity 45
on the bottom. The air-pipe S' is now con-
nected with the pressure in the reservoir and
the pipe S with the atmosphere by turning the
cocks in the pipes to the proper position. The
piston E will now be forced to descend and 50
cause the plate A and the connecting-rods B
to force the tongs inward, and at the same time
to seize and inclose within their fixed grasp
whatever material their points may spread
over or weight may be able to gather up. 55
The hoisting apparatus is now set to work and
the apparatus and its inclosed load is raised,
and by again reversing the pressure from the
top to the bottom of the piston by a change of
the cocks the load may be emptied in any 60
desired deposit, the tongs having been opened
by the air-pressure, as in the first instance.

Having now fully described my dredging
and grappling apparatus, what I claim as my
invention is—

The combination, in a power-dredging ap-
paratus substantially as herein set forth, of
the combining - ring connected to the power-
piston, and by connecting-rods jointed to the
outside of the grappling-tongs, the latter be- 70
ing centrally pivoted to the frame by which
the power-cylinder is supported, with the flexi-
ble raising and lowering apparatus and flexi-
ble power-supplying pipes, all constructed and
arranged to operate substantially as described.

HEMAN CLARK.
